UNITED STATES PATENT OFFICE.

HAMILTON E. SMITH, OF PHILADELPHIA, PENNSYLVANIA.

WASHING-MACHINE.

SPECIFICATION forming part of Letters Patent No. 655,587, dated August 7, 1900.

Application filed October 28, 1899. Serial No. 735,115. (No model.)

To all whom it may concern.

Be it known that I, HAMILTON E. SMITH, a citizen of the United States, residing at Philadelphia, in the county of Philadelphia and State of Pennsylvania, have invented new and useful Improvements in Washing-Machines, of which the following is a specification.

This invention relates to washing-machines of the kind employing an oscillating agitator, such as shown in my Patent No. 183,717, dated October 24, 1876, and has for its object to provide an adjustable partition operating between the two radial wings, whereby the amount of agitation to which the garments or other articles being washed are subjected may be varied as circumstances may require.

I have illustrated my invention in the accompanying drawings, in which—

20 Figure 1 is a transverse sectional view through a machine embodying my invention. Fig. 2 is a longitudinal sectional view through the agitator, and Fig. 3 is a detail view of the adjustable partition.

25 The reference-numeral 1 indicates a cylindrical casing having a door 2, affording access to the interior. Within this casing is mounted the agitator 3. Said agitator comprises two circular perforated heads 4, which are rigidly connected by two curved perforated blades or wings 5, which converge from the periphery of said heads toward a point outside of their common center. The inner edges of these blades do not meet, however, a space 6 being 35 left between them, in which works the adjustable partition 7. Said partition is provided along its upper edge with a rounded bead 8 to present a smooth surface for the articles being washed to pass over. The ends of the 40 partition 7 work in radial guides 9, provided, respectively, in the inner side of each head 4. On the inner side of each head 4 and at a point more or less removed from their peripheries is secured a lug 10, having a screw-threaded aperture in which works an adjusting-screw 11, having secured on its inner end a head 12, engaging in a locking recess 13, formed in the outer edge of the partition 7, near the end thereof. By turning the screws 45 11 in one direction or the other the partition 7 may be raised or lowered—that is, its rounded or inner edge may be moved toward or from

the axial line of the agitator. The purpose of this will be at once apparent. When the agitator is in place in the casing 1, the blades 55 or wings 5 serve to divide the interior thereof into two compartments, as it were, and as the agitator is oscillated the articles being washed are alternately thrown from one compartment into the other, sliding over first one blade 5 60 and then the other, these blades being preferably corrugated, as shown. By raising the partition 7 above the inner edges of the blades or wings 5 it will be seen that a greater resistance is offered to the passage or fall of the 65 articles from one side of the agitator to the other, and the agitation to which they are subjected is thereby increased. By lowering said partition the agitation will be correspondingly diminished.

70 It will be noted that I curve the wings or blades 5 instead of having them straight, as in my patent referred to. In practice I find that the straight wings or blades tend somewhat to force the goods in a body against the 75 sides of the case and carry them up in a compact form, while the curved wings or blades, on the other hand, will pass under the goods more readily and operate to throw them loosely to the other side of the casing, thus 80 preventing the formation of a roll or pack, which would prevent the suds from passing freely through the fabric. It will be apparent, however, that the wings or blades may be made straight or curved, as desired, although the latter construction is to be preferred and is the one illustrated in the drawings.

85 I have not herein shown the mechanism for oscillating the agitator, as any preferred 90 means for doing this may be adopted, and in practice I use substantially the same means shown in my patent referred to.

Having thus fully described my invention, what I claim as new is—

95 1. In a washing-machine, the combination with an oscillating agitator, of an adjustable partition carried by said agitator, substantially as and for the purpose described.

100 2. In a washing-machine, the combination with an oscillating agitator having two converging wings or blades, of an adjustable partition working between said blades, substantially as and for the purpose described.

3. In a washing-machine, the combination with an oscillating agitator comprising two circular heads connected by two converging wings or blades, of a movable partition working between said wings or blades, and means for adjusting said partition comprising a lug on each head having a screw-threaded aperture and a screw working in each of said apertures and operatively connected with said partition, substantially as described.

4. An agitator for washing-machines comprising two circular heads connected by two converging wings or blades, an adjustable partition working between said wings or blades, and means for adjusting said partition.

5. In a washing-machine, the combination with an oscillating agitator having two con-

verging curved wings or blades, of an adjustable partition working between said blades, substantially as and for the purpose described.

6. An agitator for washing-machines comprising two circular heads connected by two converging curved wings or blades, an adjustable partition working between said wings or blades, and means for adjusting said partition, substantially as and for the purpose described.

In testimony whereof I have hereunto set my hand in presence of two subscribing witnesses.

HAMILTON E. SMITH.
